United States Patent Office.

JOHN HARVEY, OF MARTINSVILLE, INDIANA.

Letters Patent No. 95,900, dated October 19, 1869.

FRUIT-DRYER.

The Schedule referred to in these Letters Patent and making part of the same.

To all whom it may concern:

Be it known that I, JOHN HARVEY, of Martinsville, in the county of Morgan, and State of Indiana, have invented a new and improved Fruit-Drier; and I do hereby declare that the following is a full, clear, and exact description thereof, which will enable others skilled in the art to make and use the same, reference being had to the accompanying drawings, forming part of this specification.

The object of this invention is to provide a cheap, simple, and efficient apparatus for drying fruit, and other like purposes.

The invention consists in an arrangement, in a rectangularly-shaped sheet-metal case, of heating-flues and ventilating-passages; also, fruit-holding shelves, all as hereinafter more fully specified.

Figure 1 represents a longitudinal sectional elevation, and

Figure 2 represents a plan view of my improved apparatus.

Similar letters of reference indicate corresponding parts.

A represents the case or shell of sheet-metal, and of rectangular form, the sides of which may be corrugated or crimped, for obtaining greater stiffness from thin metal.

The sides B are provided internally with brackets C, for supporting the shelves D, whereon the fruit or other articles to be dried are placed.

E represents a broad flat flue, beginning at the bottom, where it may be provided with a fire-place and grate, E', or have the heat delivered to it otherwise, and passing back and forth through the case, as shown at F G, dividing it into compartments H, I, K, L.

The said flue passes through the sides B of the case, and the vertical connections M of the horizontal parts are on the exterior of the said sides.

N represents openings in the side O, for access to the interior, or for ventilation.

These openings may be provided with doors or sliding gates, to close them, as shown in dotted lines at P.

Q represents ventilators at the bottom and top. Those at the top have covers or dampers R, connected by arms to a central disk, T, suspended from the top of the case by a pivot, by which they may be simultaneously turned for opening or closing the said ventilators. Similar dampers may be applied to the bottom also.

I provide drawers D with metal frames and wire bottoms, the said frames being made of T-shaped bars, formed of sheet-metal, and arranged invertedly.

This construction provides fire-proof shelves of cheap and durable construction.

Having thus described my invention,

I claim as new, and desire to secure by Letters Patent—

1. The arrangement of the case A B, the flue E, F, G, M, dividing the case into compartments, the ventilating-passages Q, and dampers R, all substantially as specified.

2. The improved fruit-drawers or shelves, constructed and arranged as specified.

JOHN HARVEY.
